UNITED STATES PATENT OFFICE.

JAMES M. SWEENEY, OF SOMERVILLE, MASSACHUSETTS.

LOCK.

SPECIFICATION forming part of Letters Patent No. 598,399, dated February 1, 1898.

Application filed February 12, 1897. Serial No. 623,080. (No model.)

To all whom it may concern:

Be it known that I, JAMES M. SWEENEY, of Somerville, in the county of Middlesex and State of Massachusetts, have invented a new 5 and Improved Lock, of which the following is a full, clear, and exact description.

This invention relates to that class of locks in which a casing carries a sliding bolt normally retained by a series of tumblers movable by a specially-constructed key to release the bolt and permit the same to be shot.

The object of the invention is to provide a lock the bolt of which may be operated either by a key or by a latch.

15 The invention will be fully described hereinafter and defined in the claims.

Reference is to be had to the accompanying drawings, forming a part of this specification, in which similar characters of reference indicate corresponding parts in all the figures.

Figure 1 is a plan view of my invention, showing the casing with one of its sides removed and illustrating a form provided with means for using both a latch and a key. Fig. 25 2 is a front view of the exterior of the casing. Fig. 3 is a view similar to Fig. 1 and illustrating the form of my invention in which only a key may be used. Fig. 4 is a sectional view on the line IV IV of Fig. 3. Fig. 5 is a sectional view on the line V V of Fig. 1. Figs. 6 to 9, both inclusive, are views illustrating various views of tumblers. Fig. 10 illustrates a modified form of key, and Fig. 11 illustrates a spring for actuating the bolt.

35 The form of the lock shown in Figs. 1 and 5 has a latch by which the lock may be operated freely at one side of the door, but which does not extend to the other side. For operating this other side of the lock I provide a

40 key which is inserted through an opening in the casing to actuate the tumbler. The casing is rectangular in form and comprises a rear side 12^a, a front side 12^b, and edge walls 12^c. Fixed on the inner face of the rear side

45 12^a are two cleats 13, which are longitudinally aligned with each other and parallel with the lower edge wall 12^c of the casing. This lower edge wall 12^c of the casing and the cleats 13 form a guideway in which the bolt-frame is 50 slidable. The bolt-frame has an upper run 14^c parallel with a lower run 14^a, the latter formed with a rectangular indentation 14^b.

The runs 14^c and 14^a are joined to each other by transverse runs 14^e and 14^d, to the latter of which the bolt proper, 14, is fixed. The 55 bolt 14 slides in an opening in the front edge wall 12^c of the casing. As the bolt-frame slides between the cleats 13 and the lower edge wall 12^c it draws the bolt 14 in and out of the casing, so as to engage or disengage 60 the keeper of the lock. (This keeper is not shown in the drawings.) Located just below the forward part of the cleat 13 and having a side parallel with the lower side of the cleat 13 is a block 15. Between this block 15 and the 65 cleat 13 the upper run 14^c of the bolt-frame is slidable. A tie-rod 15^a passes through the block 15 and engages with the walls 12^a and 12^b of the casing to hold the same together, the tie-rod 15 coacting with the usual tie-rods 70 or screws at the four corners of the casing.

Projecting downward from the bolt-frame and at the forward portion of the indentation 14^b is an arm 16, carrying a rearwardly-extending pin 17, which pin holds the front end 75 of an expansive spring 18. The rear end of the spring 18 is held by a pin 19, projecting forwardly from a standard 20, secured to the rear wall 12^a of the casing. The spring 18, mounted as described, serves to press the 80 bolt-frame and the bolt to the position shown in Fig. 1. When the bolt-frame is moved rearward, it is operated against the tension of the spring 18.

Mounted in the casing and extending transversely between the sides 12^a and 12^b is a shaft 21, on which the tumblers *a*, *b*, *c*, *d*, *e*, *f*, *g*, *h*, *i*, *j*, and *k* are mounted. The tumblers *a* and *k* are duplicates of each other. The tumbler *k* is shown in full lines in Fig. 90 1 and has a shank 22, perforated to receive the shaft 21 and having its lower edge inclined so as to coat with the ward of the latch-shank, as will be described hereinafter. The main portions of the tumblers *a* and *k* have each a shoulder 23 projecting downward 95 therefrom and normally adapted to rest on the rear extremity of that portion of the lower run 14^a of the bolt-frame, which portion forms the indentation 14^b. This supports the tumblers *a* and *k* in the position shown with reference to the tumbler *k* in Fig. 1, so that the upwardly-projecting finger 24 of each tumbler will lie in a line directly beneath the line 100

of the cleat 25, which is secured to the lower side of the run 14^a of the bolt-frame and which moves with the bolt-frame. If either of the fingers 24 engage with the cleat 25, the bolt-frame will be locked with the tumbler carrying the engaged finger 24, and it will be impossible to shoot the bolt. The lower rear portion of each tumbler *a* and *k* has a curved edge 26, adapted to lie out of the path of the ward of an authorized key. However, should an unauthorized and improper key be used the edges 26 will be engaged by the ward of such improper key and the tumblers *a* and *k* will be raised to engage the fingers 24 with the cleat 25 and make it impossible to shoot the bolt.

The tumbler *f* is shown in plan view in Fig. 7 and has a shank, a finger 28, an arc-shaped rear edge 29, and a shoulder 30. The shoulder 30 normally bears on the upwardly-extending portion 14^b of the lower run 14^a of the bolt-frame, while the finger 28 is in transverse alignment with the fingers 24, so that when the tumbler *f* is raised the finger 28 of the tumbler *f* is of such a disposition that the tumbler will not be engaged by the ward of a key which is authorized. However, should an improper key be turned in the lock this key will engage with the tumbler *f* and raise the same to lock the finger 28 with the cleat 25. All of the remaining tumblers *b*, *c*, *d*, *e*, *g*, *h*, *i*, and *j* (types of which are shown in Figs. 6, 8, and 9) have downwardly-extending portions 31, each adapted to normally engage the rear face of the upwardly-extending portion of the run 14^a of the bolt-frame, as shown in Fig. 1. When this engagement exists, it will be impossible to move the bolt-frame rearward to withdraw the bolt from the keeper. When, however, the projections 31 and the bolt-frame are disengaged, the bolt-frame may move rearward.

Each tumbler *b*, *c*, *d*, *e*, *g*, *h*, *i*, and *j* has a rearwardly-projecting portion 32, adapted to be engaged by the ward of an authorized key, so that the tumblers will be raised and the projections 31 disengaged from the bolt-frame. An unauthorized key, however, will not raise the tumblers *b*, *c*, *d*, *e*, *g*, *h*, *i*, and *j*, and it will be impossible to retract the bolt-frame. The tumblers *b*, *c*, *d*, *h*, *i*, and *j* have fingers 33, adapted to engage with the cleat 25 when an unauthorized key is used. The tumblers *e* and *g*, according to the form of the invention here shown, have no fingers projecting upwardly to engage with the cleat 25. The generic feature of the tumblers *a*, *f*, and *k* is, therefore, that these tumblers do not normally have locking engagement with the bolt-frame and have fingers to extend upwardly to engage with the cleat 25 when the tumblers are operated by an unauthorized key. The generic feature of the tumblers *b*, *c*, *d*, *e*, *g*, *h*, *i*, and *j* is that they have projections extending downward to engage and hold the bolt-frame. These tumblers may or may not have fingers to engage the

cleat 25. (See the tumbler *d* and the tumbler *g*.) The key has a shank 34, carrying a ward 35, the edge of which is given a contour such as will make the key capable of performing on the tumblers those operations which have been above described as essential to the operation of the lock. The rear side 12^a of the casing is provided with a keyhole 36, through which the key may be inserted to engage the tumblers. The front wall 12^b of the casing has no key-opening, since it is not intended to use a key at the front side of the lock. The above description of the tumblers and the key discloses one of the many forms in which my invention may be embodied. It is obvious that the shape, the size, and relative dimensions of the tumblers and key may be changed to produce innumerable combinations, which will be different in every lock that is manufactured in practice. It is unnecessary for me to describe here these infinite variations, all of which are contemplated by my invention. It will also be advantageous to bevel the edges of the tumblers, which edges are engaged by the ward of the key, so as to prevent the ward from operating two tumblers in unison when such tumblers should not operate in unison.

The lower rear portion of the run 14^a of the bolt-frame is provided with a downwardly-projecting plate 37, the lower edge of which is formed with a notch adapted to receive the ward 35 of the key. The key is inserted through the opening 36. It is then turned to move the tumblers in such a manner as to free the bolt-frame. Immediately upon this operation of the tumblers the ward of the key enters the notch in the plate 37 and slides the bolt-frame. Before the ward of the key has been moved to disengage the tumblers it will have effected such a movement of the bolt-frame as will prevent the projections 31 from reengagement with the transverse portion of the run 14^a of the bolt-frame, since it will have placed the upper side of the indentation 14^b beneath the projections 31 and cause the projections to slide along said upper portion of the indentation. The ward before it leaves the tumblers will also have moved the bolt-frame so as to place the cleat 25 over or rearward of the fingers 24 and 28, so that it will be impossible for these fingers to engage the cleat 25 and prevent the bolt from being completely withdrawn, as it will be by the immediately subsequent movement of the key.

It will be understood that when the form of the ward of the key is changed to accord with the changes in the tumblers the plate 37 must be also changed to properly coact with the key. Fig. 10 shows one of the changes in the form of the key-ward, in which event it will be necessary to provide two plates 37, respectively located adjacent to the front and rear walls of the lock-casing.

The lock is operative at the front side by a knob 38, carried on a shank 39, journaled in

the walls 12^a and 12^b of the lock-casing and running directly above the upper portion of the walls of the indentation 14^b in the bolt-frame. Carried at the upper side of the upper portion of the walls of the indentation 14^b are two racks 40, with which the pinions 41, carried on the shank 39, respectively engage. The turning of the shank 39 will therefore cause the bolt-frame to slide, so as to move the bolt in and out of the keeper. It is intended that the turning of the knob 38 will at all times operate the bolt. It is necessary, therefore, to cause the turning of the shank 39 to raise the tumblers as well as operate the pinions 41. To raise the tumblers, therefore, I provide the shank 39 with a ward 42, adapted to engage the lower edges of the shanks of the tumblers b, c, d, e, g, h, i, and j. Consequently when the shank 39 is turned the wards will raise the tumblers and at the same time will move the bolt-frame by the operation of the pinions 41. The lower edges of the shanks of the tumblers above mentioned are curved to form inclined surfaces against which the ward 42 may move.

The form of the invention shown in Figs. 3 and 4 is in all essential respects the same as in Figs. 1 and 5. The only difference is the omission of the knob 38 and its appurtenant parts. In this form both the walls 12^a and 12^b have keyholes 43, so that the key may be inserted from either side of the lock. The lock therefore can only be operated by the key.

In the drawings I have shown the upper part A of the casing reserved for the reception of any suitable form of latch. This of course has nothing to do with my invention, but is only a matter for the mechanic in constructing the lock.

The spring 18 will press the bolt-frame and its bolt continually to the position shown in Figs. 1 and 3. As soon, therefore, as the positive pressure of the latch or key is released the spring 18 will assert itself to project the bolt-frame and bolt to engagement with the keeper. This spring may be useful in some forms of the invention and not useful in others. It is useful in the form shown in Figs. 1 and 5, for, since the latch enables any one to operate the lock at any time, it is well to have a bolt continually engaged with the keeper. In the form of the invention shown in Figs. 3 and 4, however, it may sometimes be advantageous to substitute for the spring 18 the spring shown in Fig. 11, which consists in a resilient strip 44, fixed to the forward edge wall 12^c of the lock-casing and having a bent free end 45, adapted to engage either with a recess 46 in the bolt-frame or with the lower front edge of the bolt-frame, so as to hold the bolt-frame in either of two positions. Consequently when the key is inserted to move the bolt-frame, so that the lock will be disengaged from the keeper, the spring 44 will hold the bolt in this disengaged position. When the key is returned to en-

gage the bolt with the keeper, the force of the spring is overcome by the positive pressure of the key and the bolt is moved outward, whereupon the bent end 45 of the spring enters the recess 46 and prevents the bolt from being shaken out of the keeper. The upper run 14^c of the bolt-frame is provided with two recesses 47, adapted to be engaged by a bolt 48, carried in a guideway 49, attached to the front wall 12^b of the lock-casing. The front wall 12^b has a slot 50 therein, through which the operating-pin 51 of the bolt 48 extends. The bolt 48 has two notches capable of being engaged by a spring-keeper 52, carried by the guide 49. This keeper holds the bolt 48 in either of two positions. The bolt 48 may engage with either of the recesses 47. When engaged with one recess, it holds the bolt-frame with its bolt 14 engaged with the keeper of the lock. When the bolt 48 is engaged with the second recess 47, it holds the bolt-frame and its bolt 14 inward and in disengagement from the keeper of the lock.

Having thus described my invention, I claim as new and desire to secure by Letters Patent—

1. The combination with a casing, of a bolt slidable therein, a tumbler coacting with the bolt, a shank revolvably mounted within the casing, gearing sliding the bolt from the shank, and a ward carried by the shank and capable of operating the tumbler, substantially as described.

2. The combination with a casing, of a bolt slidable therein, a rack carried on the bolt, a shank revolvably mounted adjacent to the bolt, a pinion carried by the shank and engaging the rack, a tumbler mounted within the casing and coacting with the bolt, and a ward carried by the shank and engaging the tumbler to operate the same, substantially as described.

3. The combination with a casing, of a bolt-frame mounted to slide therein, the bolt-frame having an indentation at its lower portion, a rack carried by the upper wall of the indentation, a shank revolvably mounted within the casing at a point above the rack, a pinion carried by the shank and meshing with the rack, a tumbler pivoted within the casing and engaging the bolt-frame, and a ward carried by the rack and capable of engaging the tumbler to operate the tumbler, substantially as described.

4. The combination with a lock-casing, of a bolt-frame slidably mounted in the casing, the lower portion of the bolt-frame being formed with an indentation producing an interior shoulder, a tumbler mounted at its forward end on the casing, the said tumbler having a downwardly-extending portion at the rear of the pivot forming a shoulder adapted to normally engage with the said interior shoulder on the bolt-frame to hold the same, and means whereby the said tumbler

is disengaged from the bolt-frame and the bolt-frame is moved, substantially as described.

5. A lock having a casing, a bolt slidable within the casing and having a skeleton frame comprising an upper and a lower run connected by end runs, the lower run being formed with an indentation producing an interior shoulder, a tumbler inclosed by said bolt-frame and pivotally attached at its forward end to the casing, the said tumbler having a downward extension at the rear of the pivot adapted to engage the interior shoulder on the lower run of the bolt-frame to hold the bolt, and a spring located within the indentation at the lower portion of the bolt-frame and engaging the casing and bolt-frame, substantially as described.

6. The combination with a lock-casing, of a bolt slidable in the casing and having a skeleton frame, the lower portion of the bolt-frame being formed with an offset producing an interior shoulder, a tumbler pivotally mounted within the casing and inclosed by the bolt-frame, said tumbler having a downwardly-extending portion normally engaging with the interior shoulder of the bolt-frame, and also having an upwardly-extending finger located opposite to the shoulder, a cleat extending downward from the upper run of the skeleton bolt-frame, and capable of being engaged by the said finger and a plate extending downward from the upper run of the bolt-frame at the rear of the said cleat, and located adjacent to the tumbler, as and for the purpose set forth.

7. A lock having a tumbler pivotally mounted on the casing of the lock, a bolt having a skeleton frame inclosing the tumbler and normally engaged by the tumbler to hold the bolt in position, and a second tumbler also mounted on the casing of the lock and inclosed by the bolt-frame, the said second tumbler being normally out of locking engagement with the bolt-frame and capable of being moved into engagement with the bolt-frame, substantially as described.

8. A lock having a series of tumblers pivotally mounted on the casing of the lock, a bolt having a skeleton frame inclosing the tumblers and normally engaged by said tumblers to hold the bolt in position, and a second series of tumblers also pivotally mounted on the casing of the lock and inclosed by the bolt-frame, the second series of tumblers normally resting loosely on the bolt-frame and out of locking engagement therewith, the said second series of tumblers being capable of being moved into engagement with the said bolt-frame, substantially as described.

9. The combination with a casing, of a bolt-frame slidably mounted therein, the said frame being formed with a shoulder, a tumbler pivotally mounted within the casing and inclosed by the said bolt-frame, the tumbler having a projection normally engaging with the shoulder of the frame to hold the bolt in

position, the said tumbler being also provided with a finger, a cleat carried by the frame and capable of being engaged by the finger, 70 and a second tumbler pivotally mounted within the casing and inclosed by the bolt-frame, the second tumbler normally resting loosely on the bolt-frame and out of engagement therewith and having a finger capable of being moved into the path of the said cleat, substantially as described.

10. The combination with a lock-casing, of a bolt slidable within the casing and having a skeleton frame, a tumbler pivotally mounted 80 within the casing and inclosed by the bolt-frame, the said tumbler having a downwardly-extending projection adapted to engage and hold the bolt-frame, and a second tumbler also pivotally mounted within the casing of 85 the lock and normally out of locking engagement with the bolt-frame, the said tumbler having an upwardly-extending finger, capable of being moved into engagement with the bolt-frame, substantially as described. 90

11. The combination with a lock-casing, of a bolt slidable in the casing and having a skeleton frame, the said bolt-frame having a rectangular indentation at its lower portion producing an interior shoulder, a tumbler pivotally mounted within the casing and inclosed by the bolt-frame, said tumbler having a downwardly-extending projection arranged to engage the said interior shoulder of the bolt-frame, and a spring located within the 100 rectangular indentation at the lower portion of the bolt-frame and connected to the casing and to the bolt-frame, substantially as described.

12. The combination with a casing, of a bolt-frame slidable in the casing, the said frame being provided with a shoulder, a tumbler mounted within the casing and having a projection normally engaging with the shoulder of the frame to hold the bolt in position, a 110 notched plate projecting from the bolt-frame and located adjacent to the said tumbler and adapted to be engaged by the instrument that moves the said tumbler, a cleat carried by the frame, and a second tumbler mounted within 115 the casing and normally resting loosely on the bolt-frame, the said second tumbler having a finger capable of being moved into the path of the said cleat, substantially as described. 120

13. The combination with a lock-casing, of a tumbler mounted on the casing and formed with a projection, a bolt-frame slidably mounted in the casing and normally engaged by said projection of the tumbler to hold the 125 bolt in position, and a second tumbler also mounted on the casing of the lock, the second tumbler being normally out of locking engagement with the bolt-frame and having a projection capable of being moved into engagement with the bolt-frame, substantially as described.

14. The combination with a casing, of a bolt-frame slidably mounted in the casing, the

said bolt-frame being formed in its lower portion with an indentation producing an interior shoulder, a tumbler pivotally mounted on the casing above the upper surface of the said indentation and formed with a projection adapted to engage said interior shoulder of the bolt-frame to hold the bolt in position, and means for disengaging the tumbler and immediately moving the bolt-frame, whereby

the upper surface of the said indentation is carried beneath the projection of the tumbler and reengagement of the said projection with the interior shoulder is prevented, substantially as described.
